UNITED STATES PATENT OFFICE.

WILLIAM O. CRAIN, OF BALTIMORE, MARYLAND, ASSIGNOR OF TWO-
THIRDS TO WISE BROS., OF SAME PLACE.

BUTTON-ATTACHING MACHINE.

SPECIFICATION forming part of Letters Patent No. 368,134, dated August 9, 1887.

Application filed June 9, 1887. Serial No. 240,715. (No model.)

To all whom it may concern:

Be it known that I, WILLIAM OLIVER CRAIN, a citizen of the United States, residing at Baltimore, in the State of Maryland, have invented certain new and useful Improvements in Button-Attaching Machines, of which the following is a specification.

This invention relates to a machine for attaching metal buttons to garments, and is illustrated in the accompanying drawings, (three sheets,) in which—

Figure 1 is a side elevation of the machine, showing the punch raised. Fig. 2 is an elevation showing a side view of certain portions and a vertical section of other portions. In this view the punch is lowered. Fig. 3 is an elevation showing a view of the side opposite or reverse to that seen in Fig. 1. Fig. 4 is a top view of the button hopper or turret and slideway. Fig. 5 is a section (larger scale) of the slideway for the buttons. Figs. 6 and 7 show side and bottom views of the turret-hopper. Fig. 8 is a section of the base on which the turret revolves, and shows also a part of the slideway. Fig. 9 is a view of the arm by which the turret is revolved. Figs. 10 and 11 are sections of the same device seen in Fig. 9, each showing a different construction. Fig. 12 is a view of the punch and follower. Fig. 13 is a sectional view of a button.

The letter A designates the frame, which has two slide-bearings, b b', for the punch C and follower D. These bearings are one above the other in an inclined axial line. This position is part of a contrivance to effect an end herein-after mentioned. The punch C is raised and lowered by a lever, E, which is pivoted in a bearing, e, at the top of the frame, and a link, d, connects the punch and lever. By depressing the free end c' of the lever the punch will be raised, and by elevating the said free end c' the punch will be lowered. The follower D is raised and lowered by a lever, F, which is pivoted by a bolt, e, near the lower part of the frame. This lever F is actuated by mechanism which is connected with the punch-moving lever E. A spring, f, is fixed to the frame A and bears on the lower side of the lever F near its end and thereby presses said end up, which results in lowering the follower D. A rock-shaft, G, in the frame has a cam, G', on it. When the flat side f' of the cam is in contact with the top of the lever F the follower D will

be lowered, as in Fig. 1; but when the round part of the cam is in contact with the lever F, 55 as in Fig. 2, the follower will be raised.

The cam-lever F is provided with an inclined bearing-plate, g, which is movable along the lever and serves as an adjustment for the movement of the follower. This plate has a 60 slot, g', and a set-screw, h, in the lever projects through the slot. It will be seen that by loosening the set-screw h the adjusting plate g may be moved so as to bring either its high or low end to a point where the cam will bear. The 65 effect of thus changing the position of the inclined plate will be to raise the follower D more or less.

The mechanism connecting the cam G' with the punch-lever E is the arm i, which is attached to the rock-shaft G, and the link j, which unites this arm with the punch-lever E. It will thus be seen that whenever the punch-lever E is moved the rock-shaft cam G' will also be moved. The result is that the punch C 75 and follower D are both moved and that their movement is properly timed.

The follower D has at its upper end a point-anvil, k. The button l passes from the turret down the slideway H to the seat l', below which 80 is the said point-anvil, by which the button is centered for the action of the punch C. The button has a concave center, k', which has position below, and the end of an eyelet, m, which is to be upset, points upward. The point-anvil k takes in the concave center k' of the button, and by lifting the latter slightly causes it to be centered. The punch C has at its lower end a point, m', which comes down into the upturned end of the eyelet, and the latter is there- 85 upon upset.

The buttons l are placed into the turret-shaped hopper I, which resembles an inverted cup, and is mounted on shaft I', having bearing in a plate, J, attached to the slideway H. 95 The plate J forms the bottom of the hopper, and the latter revolves in an inclined plane within a circular rim, J', on said plate. The turret-hopper has a central hub, n, and a set-screw, n', in the hub secures it fast to the shaft 100 I'. A hole, n'', in the wall of the turret opposite the set-screw serves for a screw-driver to have access thereto. The lower edge of the turret has slit-openings l', for the escape or discharge of the buttons one at a time into the 105 slideway H. Its wall is also provided on the

interior (see Figs. 2 and 7) with radial projecting pins o , which, as the turret revolves, serve to carry the buttons to the discharge-opening l' in the circular rim J' , and also serve to stir the buttons and place them in position where they will be certain to discharge.

The circular rim J' , which surrounds the hopper, has an undercut groove, q , which is eccentric to the shaft I' . This groove is shown in Fig. 2 and is indicated in Fig. 8. The object of this groove is to receive the rim of the buttons, and thereby insure that the buttons will take the proper position to be discharged through the opening l .

15 The inclined slideway H is formed by two parallel guide-strips, r , secured on a plate, s . The confronting edges of the guide-strips are undercut, as shown at r' , and form a groove for the buttons, which slide down on the plate s between the guide-strips. The upper end of this groove coincides with the opening l' in the rim J' , through which the button discharges. The slideway H inclines down to the seat l , and if a vertical line be drawn through said seat the slideway will be seen to be inclined at one side of said line and the punch C and follower D reversely inclined at the other side of said line.

The turret-hopper I has an intermittent revolving motion, which may be imparted to it by any suitable or known mechanism. In the present instance an arm, L , is on the shaft I' , and a rod, t , connects the arm with the punch-lever E . This arm L may be attached on the shaft I' by a pawl and ratchet or similar device. A collar, u , is fitted tight on the shaft I' and has a neck, u' , around which the ring L' of the arm fits and turns loosely. The arm-ring L has a slot, v , (see Figs. 9, 10, and 11,) 40 which extends in a tangential direction with respect to the circumference of the neck u' , and a loose pin, w , occupies the said slot. When the pin w is in the slot end closest to the neck u' , the pin will bind against the circumference of 45 said neck, and thereby the arm will be made fast to the neck; but when the pin w is in the slot end farthest away from the neck it will not bind, and the arm L will be free or loose on the neck. The arm L is thrown back and 50 forward by the action of the rod t and lever E . When thrown one way, the arm causes the shaft I' and turret to move; but when it is thrown the other way the ring L' of arm will turn freely on the neck u' , and neither the shaft nor the turret will move.

The collar u may be made fast to the shaft I' by a set-screw, x , so that it will not slip, as shown in Fig. 10; or the collar may be made fast enough to insure it to turn the turret I under ordinary conditions, but so it will slip on the shaft I in case the buttons should by any chance choke the turret and prevent it from moving. An example of this latter mode of fastening the collar is shown in Fig. 11. The 65 shaft has a groove, y , around it, a metal plug, z , in the collar fits in the said groove, a piece

of leather, z' , rests on the metal plug, and a set-screw, x' , presses the leather. This arrangement prevents the set-screw from binding rigidly on the shaft, and the result is that 70 should the turret become choked the collar will slip around the shaft.

A button-stop to arrest the button moving down the slideway when it reaches the seat l comprises an angular arm, N , pivoted at e . 75 The point end d of the arm is at the lower end of the slideway and stops the button. A spring, P , bears on the rear end of this pivoted arm and keeps the said point end normally across the lower end of the slideway. 80 When it is desired to detach or draw out a button from the slideway, a slight pull will cause the arm to yield sufficient to allow the button to pass.

The herein-described construction and position of parts insures that the buttons will move down the slideway H , which inclines at one side of the seat l , by their own gravity, and as the punch C and follower D have an axial line, which is reversely inclined at the opposite 90 side of the seat, the latter may be square or at right angles with respect to said punch and follower without having an objectionable bend or angle at the point a in front of the seat.

Having described my invention, I claim and 95 desire to secure by Letters Patent of the United States—

1. In a button-attaching machine, the combination of the punch C , the follower D , the lever F , connected with the follower, a spring 100 bearing on the lever, and a cam, G' , also acting on the said lever.

2. In a button-attaching machine, the combination of the punch C , the follower D , the lever F , connected with the follower, an adjustable inclined bearing-plate, g , on the said 105 lever, and a cam, G' , for the purpose set forth.

3. In a button-attaching machine, the combination of the punch C , a lever, E , for actuating the punch, a follower, D , and a lever, F , connected with it, a cam, G' , for actuating the follower-lever, and mechanism, substantially as described, connecting the said cam with the punch-lever.

4. In a button-attaching machine, the combination of the punch C , a button-seat, l , an inclined slideway leading to the button-seat, an inclined plate at the upper end of the slide-way having a circular rim, J' , provided with an undercut groove, q , eccentric with respect to the shaft in the center of the plate, and an outlet-opening, l' , and a bottomless turret-hopper, I , revolving within the said circular rim and provided with pins o , attached to the interior wall, for the purpose set forth. 115 120 125

In testimony whereof I affix my signature in the presence of two witnesses.
